TEMPERATURE-CONTROLLED VENDING
CABINET

Fred A. Ossanna, Jr., Austin, Tex.

Application February 9, 1950, Serial No. 143,279

5 Claims. (Cl. 312—36)

1

This invention relates to cabinets for storing and dispensing articles.

One object of my invention is to provide in a temperature-controlled cabinet for storing and dispensing various articles a novel and improved means of circulating the air within the cabinet to attain maximum heat-exchange efficiency.

A more specific object of my invention is to provide a novel and improved temperature-controlled cabinet for storing and dispensing various articles which will provide adequate air circulation therein about its heat-exchanging medium to permit stacking of said articles in spaced vertical rows therein and yet maintain such articles at desired temperatures.

Another object is to provide for a cabinet of the class described a dispensing door which will automatically preclude access being gained to the interior of the cabinet at all times and thus prevent injury to the customer or children who might be inclined to meddle with the dispensing mechanism.

Another object is to provide in a temperature-controlled cabinet for storing and dispensing various articles a shiftable secured panel which will house the selecting and dispensing controls of the cabinet and at the same time permit visual reference by the customer to the articles offered for selection and dispensation.

A further object is to provide for a cabinet of the class described a novel and improved air directing and driving mechanism whereby the air within the cabinet is circulated across its heat-exchanging medium at least twice per convolution.

These and other objects and advantages of my invention will more fully appear from the following description made in connection with the accompanying drawings wherein like reference characters refer to similar parts throughout the several views and in which:

Fig. 1 is a perspective view of a cabinet embodying the invention;

Fig. 2 is a perspective view of the cabinet when the door is open with a portion broken away to show the vertical arrangement of the articles within;

Fig. 3 is a vertical sectional view along line 3—3 of Fig. 2;

Fig. 4 is a fragmentary vertical sectional view along line 4—4 of Fig. 3.

One embodiment of my invention includes, as shown in Figs. 1—4, a cabinet C which has a piano-hinged type door 5. This door 5 is provided with a coin slot 5a and a heat-insulation type gasket

2

6 around its outer edge and a pair of clamps 7 for co-operation with a pair of anchors 8 which are secured to the edge of the main body portion B of the cabinet C, as shown. Dividing the main body portion B of the cabinet C is an upright baffle plate 9 which extends from top to bottom and from the back wall of the main body portion B to a semi-transparent heat-insulating sheet 10 and a triangularly shaped heat-insulating panel 11. This panel 11 and the back wall of the main body portion B together with two diagonally disposed baffle plates 12 and 13 form a casing which seals the air chamber 14 to prevent the escape of the cool air contained therein. As shown, the diagonal baffle plates 12 and 13 extend from the bottom of the upright baffle plate 9 to the sides of the cabinet C. This baffle plate 9 has an aperture 15 of substantial size in its upper portion as shown in Fig. 3. Suitably secured 15 within the main body portion B and in the upper portion of the air chamber 14 on a shoulder 16 which extends around the interior of the cabinet C, as shown in Fig. 3, are a plurality of spaced vertical dispensing racks 17 of the type disclosed 20 in my pending application for patent, S. N. #115,756 entitled "Vending or Dispensing Machine for Cylindrical Containers," now Patent No. 2,628,875, February 17, 1953. The articles 18 to be dispensed are stacked and stored in these 25 spaced racks as shown until dispensed. The transparent heat-insulating sheet 10 is provided with an air-tight seal and provides one wall for the area in which the articles 18 are stored, as shown. It is constructed of any suitable transparent heat-insulating substance and is secured to the main body portion of the cabinet by any suitable means which will permit easy access to the 30 interior for refilling the racks 17. Disposed just beneath the racks 17 is a series of heat-exchanging tubes or coils 19 arranged in horizontal grid-pattern, as shown in Fig. 4.

Extending transversely through the lower portion of the baffle plate 9 is a curved fan housing 20, the open ends of which extend slightly upward. Mounted within the fan housing 20 on a drive shaft 21 is a fan 22. The shaft 21 is rigidly mounted in a bearing 23 which is welded or otherwise suitably secured to two baffle plates 24 where they cross each other at right angles, as shown in Figs. 3 and 4. These baffle plates 24 serve to brace the shaft 21 and maintain it in rigid position. The drive shaft 21 extends horizontally through a heat-insulated fitting 13a in the baffle plate 13 to a motor 25 or other source 35 of power. The motor 25 is located in the recesses

formed by the plates 12 and 13 outside the air chamber 14, of course, as is the compressor 26 which is connected to the coils 19 for refrigeration purposes by a pair of conduits 27 and 28. The area surrounding the motor 25 and compressor 26 is ventilated by means of an air vent 29. The operation of the compressor 26 is controlled by a pair of conventional thermo-electric switches (not shown) within the air chamber 14.

The door 5 is provided with a transparent panel 30 and a plurality of dispensing chutes 31 which are aligned with the racks 17. Each dispensing chute is equipped with a selection button 31a. Disposed within each dispensing chute 31 is an inverted L-shaped dispensing door 32 which is pivotally mounted at its corner or angle to the upper wall of the dispensing chute by a pinion 33 which in turn is mounted in the sides of dispensing chute 31. The dispensing door 32 is faced downwardly and toward the interior of the cabinet C, as best shown in Fig. 3, so that one of its arms 32a is normally abutting the top wall of the dispensing chute 31 and its other arm 32b is normally in vertical position. The edges of each dispensing door 32 are provided with a low resistance surface to prevent the possibility of frosting and, as a result, jamming of the door. Both of the arms 32a and 32b are of dimensions to provide a close fit with the walls of the dispensing chute 31 so as to reduce the loss of refrigeration to a minimum when an article is dispensed.

Disposed just above the dispensing chutes 31 and insulated therefrom as shown is a compartment 34 which houses the selector switches and the selector control harness (not shown) which together control the selection and dispensation of the articles. Positioned just above compartment 34 and its associated insulation is a cold light tube 35 arranged to illuminate the articles 18 and at the same time shield the light from the eyes of the customer as he looks through the panel 30 at the articles 18.

Operation

My invention is easy and safe to operate. The customer merely inserts the required coin into the coin slot 5a, and makes his selection by pressing the selector button 31a aligned with the rack 17 containing the desired article 18. The selector button 31a will cause its selector switch to close whereby an electrical circuit is established to operate the selector control harness. The selector control harness causes the rack 17 to eject the desired article 18 into the vend chute 31. The article 18 strikes the dispensing door 32 as it rolls down the dispensing chute incline causing its normally upright portion 32b to pivot to a position substantially horizontal and its normally horizontal portion 32a to pivot to a substantially vertical position. It can be readily seen that whenever the dispensing door 32 is moved to this position it is still impossible for anyone to insert his hands into the interior of the cabinet and come in contact with the dispensing mechanism. This dispensing door 32 automatically precludes such an eventuality regardless of its position.

The air contained within the air chamber is circulated by the fan 22. The curved shape of the fan housing 20 gives the air a somewhat upward direction as it is expelled from the housing. This upward direction is accentuated by the diagonal baffle 12 to cause the air to rise upwardly between the coils 19. As the air passes across these coils 19 it is heated or cooled depending

upon the temperature of the coils relative to that of the air. In the embodiment shown, the coils 19 are refrigerating coils and so the air would be cooled. Thereafter the air is driven upwardly between the spaced racks 17 and the articles 18, cooling the latter to the desired temperature. When the cool air reaches the upper portion of the air chamber 14 it is forced through the baffle plate aperture 15 and downwardly between the racks 17 and articles 18 on the other side of the baffle plate 9. This air which is forced downwardly is warmed by the articles 18 as it progresses. When it reaches the lower levels of the racks 17 it once again passes between the refrigerating coils 19 whereby it is cooled substantially. Thereafter it is drawn through the fan housing 20 by the fan 22 and re-circulated.

One big advantage provided by my structure is the fact that the air which does the cooling of the articles 18 passes over and between the coils 19 twice during each convolution. This provides a substantially more efficient cooling of the circulating air and consequently more efficient cooling of the articles to be dispensed.

Another important feature of my structure is the insertion within the swingably secured door 5 of the heat insulating transparent panel 30 and the compartment 34 which houses the selection and dispensing controls. It is possible for the customer to view the entire array of articles 18 in the racks 17 in making his selection. This provides an attractive display for the articles 18 which is reflected in increased sales of the same. Also, the selection and dispensing controls are made readily accessible for inspection and repair without exposing the interior of the air chamber 14 to the warmer atmosphere and thereby increasing its temperature. These controls can be repaired or inspected while the door is open without any substantial increase of temperature within the air chamber 14, since the only possible avenue of escape of the cold air is the small area surrounding the lowest article 18 in each row 17.

It will, of course, be understood that various changes may be made in the form, details, arrangement and proportions of the parts without departing from the scope of my invention.

What I claim is:

1. In a cabinet for dispensing articles having opposite side walls and a top and bottom for storing articles therebetween in spaced vertical rows and for maintaining the air contained therein in heat exchange relationship with the articles, an upright dividing member extending between opposite walls of said cabinet, said member being formed to leave a transverse aperture adjacent the top of said cabinet for the passage of air therethrough, air-flow-directing members extending upwardly and laterally from the lower portion of said dividing member to said side walls to form a housing at the lower end portion of said cabinet and outside the path of air flow for housing generating mechanism used for maintaining said air in heat exchange relationship with such articles, and means for positively circulating said air in a flow upwardly between the articles on one side of said dividing member and through said aperture and downwardly between the articles on the other side of said member and then back to said first mentioned side of said member for re-circulation.
2. In a machine for storing articles in spaced vertical rows and for selectively dispensing the same, a cabinet having top, bottom, back, and side walls and a horizontal shoulder extending in-

75

wardly therefrom in spaced relation above said bottom, the space above said shoulder being adapted for containing article supporting means, an upright dividing member extending between the opposite side walls of said cabinet and defining in conjunction therewith a pair of substantially vertical ducts, said member being formed to leave a transverse aperture adjacent the top of said cabinet for intercommunication between the upper ends of said ducts, a casing disposed below said horizontal shoulder and having communication with both of said ducts, said casing having a lower wall defining a deflector for guiding circulating air upwardly into one duct and downwardly from the other duct to the central portion of said casing, means within said casing for positively circulating air through said ducts and over and about the vertical rows of articles contained therein and a heat exchanger element traversing the circulatory system formed by said casing and said ducts.

3. The structure set forth in claim 2 and said casing being entirely housed in a casing between said horizontal shoulder and the bottom of said cabinet and defining therewith exteriorly of said second mentioned casing a compartment for housing operating mechanism of a heat exchanger system.

4. In a cabinet for dispensing articles having opposite side walls and a top and bottom for storing articles therebetween in spaced vertical rows and for maintaining the air contained therein in heat exchange relationship with the articles, an upright dividing member extending between opposite walls of said cabinet, said member being formed to provide a transverse aperture adjacent the top of said member for the passage of air therethrough, means for positively circulating said air in a flow upwardly between the articles on one side of said dividing member and through said aperture and downwardly between the articles on the other side of said member and then back to said first mentioned side of said member, air-flow-directing members adjacent said circulating means formed to impart to said air flow the directional curvature necessary for recirculation of said air, said air-flow-directing members extending diagonally from the lower

portion of said dividing member to said side walls to form an air chamber within said cabinet and to provide recesses beneath said cabinet and outside of the path of said air flow for housing generating mechanism required for maintaining said air in heat exchange relationship with said articles.

5. In a machine for storing articles in spaced vertical rows and for selectively dispensing the same, a cabinet having opposite side walls and a top and bottom for storing articles therebetween in spaced vertical rows and for maintaining the air contained therein in heat exchange relationship with the articles, an upright dividing member extending between opposite walls of said cabinet, said member being formed to leave a transverse aperture adjacent the top of said cabinet for the passage of air therethrough, a plurality of spaced heat exchange elements extending substantially horizontally and transversely across the interior of said cabinet at a level adjacent the lower end portion of said dividing member and across the entire width of said cabinet, an air chamber formed by said bottom with said side walls and disposed immediately below said heat exchange elements, and means within said air chamber for positively circulating said air in a flow directed upwardly between the articles on one side of said dividing member and through said aperture and downwardly between the articles on the other side of said member and thence back between said heat exchange elements to be recirculated by said means.

FRED A. OSSANNA, JR.
